UNITED STATES PATENT OFFICE.

WILLIAM H. MATTHIES, OF HACKENSACK, NEW JERSEY, ASSIGNOR, BY MESNE ASSIGNMENTS, TO WESTERN ELECTRIC COMPANY, INCORPORATED, A CORPORATION OF NEW YORK.

TELEPHONE-EXCHANGE SYSTEM.

Application filed March 26, 1925. Serial No. 18,391.

This invention relates to automatic telephone exchange systems and more especially to telephone systems wherein line finders are employed for extending calling lines to 5 idle outgoing trunks.

In automatic telephone systems which employ power driven line finder switches in cooperation with the so-called panel type of multiple bank, an appreciable interval 10 elapses under certain conditions between the moment of initiation of a call and the moment when a calling line is connected to an outgoing trunk. This feature is particularly objectionable in systems where re- 15 turns to normal line finder switches are employed or wherein the multiple banks comprise a considerable number of called line terminals. For example, should the multiple bank be so arranged as to accommodate one 20 hundred calling lines an appreciable time elapses before a calling line is connected with an outgoing trunk, more especially when this calling line is located in the upper portion of the bank.

25 It is an object of this invention to greatly reduce the time required for a line finder switch to extend a calling line, by providing novel hunting and circuit switching arrangements.

30 According to one feature of the invention two brushes of a line finder switch are simultaneously tripped to hunt simultaneously for calling lines in different groups.

Another feature of the invention relates 35 to a switch of the power driven type comprising a plurality of brushes, certain of said brushes being adapted to hunt for calling lines when the switch is moving in one direction and other of said brushes being 40 adapted to hunt for calling lines when the switch is moving in an opposite direction.

Another feature relates to a continuously 45 hunting line finder switch wherein the brushes are tripped in pairs.

50 A still further feature relates to an arrangement of line finder switches, certain of the switches being adapted when moving in one direction to hunt for a particular calling line and other of the switches being adapted when moving in an opposite direction to hunt for the same calling line.

A further feature of the invention relates to the novel means for tripping line finder 55 brushes in pairs.

The invention is described in connection 55 with a 400 point power driven panel bank line finder switch for the purpose of showing one advantageous use of the invention. It is understood, however, that the invention is capable of a wide variety of uses and is 60 to be limited only by the scope of the appended claims.

Referring to the drawing, Fig. 1 shows a number of subscribers' lines with the line and cut-off relays individual to each line as 65 well as a common start wire.

Fig. 2 shows a portion of the line finder multiple bank and the cooperating multiple brushes. The portion of this figure to the left of the broken line represents the front 70 of the line finder bank and the portion to the right of the broken line represents the rear of the same line finder bank.

Fig. 3 shows groups of control relays, each group being individual to one of the line 75 finder switches shown in Fig. 2.

Fig. 4 represents a side view of one of the multiple brushes represented schematically in Fig. 2.

Fig. 5 represents a plan view of a multiple 80 brush.

When Figs. 1, 2 and 3 of the drawing are arranged as shown in Fig. 6, sufficient details of the circuit arrangements are disclosed to enable a complete understanding to be 85 obtained of a preferred form of carrying out the invention.

General description.

Referring to Fig. 2 there are shown two 90 groups of power driven line finder switches, one group including switches 201 and 202, the other group including switches 203 and 204. Switches 201 and 202 together with the associated driving apparatus are located in 95 the front of the line terminal bank, while switches 203 and 204 together with their associated driving apparatus are located in the rear of the same bank. As is well understood, the various sets of multiple terminals extend outwardly from the front and rear of the panels. For the purpose of securing simplicity in the drawings the front and rear portions of the banks are shown in developed form.

100 In Fig. 2 there are shown four panels to a bank numbered 0, 1, 2 and 3 successively. In practice each panel would accommodate

multiple terminals of one hundred calling lines. These panels may be made according to the process disclosed in United States Patent No. 1,127,741 to A. F. Dixon issued 5 February 9, 1915. Each panel is composed of strips of metal and interposed strips of insulation. Each metallic strip has lugs projecting from the front and rear of the panel and adapted to be engaged with a 10 wiping action by the multiple brushes when these brushes are tripped. Four of these strips are provided for each line corresponding to the tip, ring, sleeve and hunting conductors thereof. The several panels are separated by metallic strips 205, 206, etc., in which are positioned pins 207, 208, 209, etc. The purpose of these pins will be described in detail hereinafter.

Each line finder switch comprises four 20 multiple brushes 211, 212, etc., mounted upon a brush rod, as rod 214. Each multiple brush is rigidly secured to its respective rod and comprises four contact springs. One of the multiple brushes is shown in comparative detail in Figs. 4 and 5 of the drawing. Associated with each brush there is a trip lever 3 and a reset lever 4. The brush shown in Figs. 4 and 5 is in its normal position, wherein the contact springs 6, 7, 8 and 25 9 are maintained out of engagement with bank terminals 10, 11, 12 and 13 by means of the insulating spacing pieces 14 and 15. When certain of the multiple brushes during the progress of hunting for a calling line, 30 approach the limit of their upward movement, the trip lever 3 engages the pin 16 which projects downwardly from the top of the frame work of the panel with which the brush cooperates. A slight further upward movement of one of these brushes therefore, causes pin 16 to press downwardly on the trip lever 3 which, together with reset lever 4, is rotated, causing the spacing pieces 14 and 15 to be moved, whereby 35 springs 6, 7, 8 and 9 are brought into cooperative relation with the bank terminals 10, 11, 12 and 13 respectively. Simultaneously with the tripping of the brush as above described the direction of the motion of the brush rod 17 is reversed and the brush is caused to hunt over the terminal bank while 40 descending. Should the calling line fail to be located by the brush during its downward hunting movement the reset lever 4 engages the lower plate 18 of the panel, whereby 45 reset lever 4 and the trip lever 3 are restored to the position indicated. After the resetting of the brush as described, the direction of motion of rod 17 is again reversed 50 and the brush 25 is again moved upwardly, in this case, however, brush 25 is untripped. From the above description it is seen that brush 25 during its upward movement is out of engagement with the calling line terminals and its hunting action occurs only dur-

ing the downward movement of the brush rod 17. In practice however, each brush rod is equipped with four multiple brushes and certain of these brushes will be mounted on the brush rod in the opposite manner to the mounting of brush 25. Thus while brush 25 hunts only during downward movement other brushes on the same rod may hunt during upward movement as will appear from the general and detailed description. The structure and method of tripping and resetting a multiple brush such as shown in Figs. 4 and 5 is fully described in the United States patent to Craft and Reynolds No. 1,122,696, issued January 5, 1915.

Referring to Fig. 2 the multiple brushes 211, 216, 212 and 217 cooperating with panels No. 0 and No. 2 in the front of the bank, and brushes 213, 237, 238 and 239 cooperating with panels No. 1 and No. 3 in the rear of the bank are secured to their respective brush rods so that the trip and reset levers are below the associated contact springs, as shown in Fig. 4. Brushes 218, 219, 220 and 221 cooperating with panels No. 1 and No. 3 in the front of the bank, and brushes 240, 241, 242 and 243 cooperating with panels No. 0 and No. 2 in the rear of the bank are secured to their respective rods in an inverted manner, that is, with the trip and reset levers above the corresponding contact springs. It will be apparent that all brushes cooperating with panels No. 0 and No. 2 in the front of the bank and all brushes cooperating with panels No. 1 and No. 3 in the rear of the bank make contact with the line terminals only during the downward movement of their respective brush rods, while the brushes cooperating with panels Nos. 1 and 3 in the front and panels No. 0 and No. 2 in the rear make contact only during upward movement of their respective brush rods. That is to say, certain brushes are downwardly hunting while others are upwardly hunting. Consequently when the downwardly hunting brushes reach the limit of their downward movement the reset levers of these brushes will encounter the corresponding metal strips as 205, 206, etc., and the downwardly hunting brushes will be reset. The opposite is true in the case of the upwardly hunting brushes, since the reset lever is above the contact springs, when these brushes reach the top of their respective panels the reset operation is effective.

An inspection of Fig. 2 will reveal the fact that projections 226, 227, 207, 208, etc., are provided in certain of the panel plates. These projections correspond to the pin 16 of Figs. 4 and 5 and they may be attached to the panel frame plates 205, 206, etc., in any suitable manner and their purpose is to trip the associated brushes when they have reached the limit of their movement. It

will also be observed that in the rear of the bank these pins are attached to different plates from those on the front of the bank. For example, pins 207 and 208 are located 5 in the front of the bank and project from the plate 206 in an upward and downward direction, while pins 228 and 229 are located in the rear of the bank and project through plate 223. In Fig. 2 the updrive circuit is 10 shown prepared by means of switches 236, 259, etc., for all the brush rods. Accordingly the brushes No. 0 and No. 2 on the front and the brushes No. 1 and No. 3 on the rear of the bank are untripped as indicated 15 by the position of the spacing pieces 232, 246, 233, 272, 247, 248, etc., while brushes No. 1 and No. 3 in the front and brushes Nos. 0 and 2 in the rear are shown tripped. The finders have no normal position but are arranged 20 to remain in the last operated position.

Assume that line finders 201, 203 and 204 alone are idle when a call is initiated on line 101 then all these idle line finders are 25 started simultaneously to hunt for the calling line. Brush 220 on the front of the bank is tripped but it is above the terminals of the calling line 101. However on the rear of bank it will be noted that finder 30 switch 204 is approaching the limit of its upward movement as indicated by the engagement of pin 251, with the switch arm 252. Accordingly the downwardly projecting pin 230 engages the trip lever of brush 35 239, as hereinbefore described, causing the contact springs of brush 239 to assume the operated position. Immediately thereafter the arm 252 closes the circuit of the downdrive magnet 249. In this case brush 239 being 40 tripped hunts over the terminals of panel No. 3 and when the calling line 101 is reached the start circuit is opened causing the deenergization of the driving magnets of finders 201, 203 and 204. Finder 204 is immediately 45 rendered busy and finders 201 and 203 remain in this position until the initiation of another call.

Detailed description.

Let it be assumed that when the subscriber at line 101 initiates a call the finder switches 201, 203 and 204 are idle and switch 202 is busy. The removal of the receiver by the calling subscriber causes line relay 102 to operate by means of a circuit which is completed from battery through the winding of 55 said relay, right contact of relay 103, ring conductor of the calling line, through apparatus at the calling substation, over the tip side of the line to ground at the left contacts of relay 103. Relay 102 in operating extends ground through its left contacts, to the start wire 151, to cause the operation of start relays 301, 303 and 304. Since finder 60 202 is assumed busy, relay 305 individual

thereto is operated in the manner described hereinafter thus preventing the operation of start relay 302. Relay 102 also connects battery through the right contacts of said relay to the hunting conductor 152, and 70 thence to the multiple hunting terminals of line 101 in panel No. 3. A circuit is now completed for the updrive magnets 231, 253 and 254. The circuit for operating magnet 231 may be traced from battery through the 75 winding of said magnet, lower contact of transfer switch 236, conductor 270, left contacts of relays 301 and 306 to ground at the left contact of relay 307. Similar circuits may be traced for the updrive magnets 253 80 and 254.

The energization of magnet 231 causes brush rod 214 to ascend until the reset lever of brush 220 encounters the plate 225 whereby the contact springs of brush 220 are removed from operative relation with the No. 3 panel contacts. Immediately thereafter projection 256 engages the transfer switch arm 236 causing the same to engage its upper contact. The circuit above traced for energizing magnet 231 is now transferred to magnet 257 whereby brush rod 214 is caused to descend. The brush 220 having been reset, this finder during its downward movement is unable to hunt for the calling line. 95 As already noted finder 204 is shown near the limit of its upward movement, so that when updrive magnet 254 is energized as above mentioned the slight further upward movement of brush rod 258 causes pin 230 100 to engage the trip lever of brush 239 whereby the contacts of brush 239 are brought into cooperation with the terminals of panel No. 3. The transfer switch 252 having been operated as described in connection with 105 switch 236 the downdrive magnet 249 is now energized and rod 258 descends, trailing the springs of brush 239 over the terminals of the No. 3 panel. It may be gathered from the positions of brushes 220 and 239 110 as shown in the drawing, that brush 239 will be the first to reach the terminals of line 101 during the downward movement, whereby a circuit is completed from battery 115 through the right contacts of relay 102, conductor 152, hunting terminal and corresponding hunting spring of brush 239, conductor 351, both windings of relay 308, winding of relay 310 to ground at the contacts of relay 309. Relay 308 operates in this last mentioned circuit but the resistance of its right hand winding is sufficiently high 120 to prevent the energization of relay 310. When relay 308 attracts its armature, however, the right hand winding of said relay is short circuited thus permitting sufficient current to flow through the winding of relay 310 to cause the operation of the same. Relay 310 in operating breaks the circuit 125 for the downdrive magnet 249 thus stopping 130

the brush 239 on the terminals of the calling line. A circuit may now be traced from battery, through the left winding of relay 311, front contacts of relay 310, to ground 5 at the contact of relay 313. Relay 311 locks by means of a circuit which is completed from battery, through the left winding and left front contacts of said relay, normal contacts of relay 312 to ground at the outer 10 front contacts of relay 311. Relay 311 also extends ground through its outer front contacts and thence through the winding of relay 309, left outer back contacts of relay 314, conductor 353, sleeve spring of brush 15 239, and thence to the sleeve conductor of line 101, to battery through the winding of cut off relay 103. Relays 103 and 309 are energized in this circuit. Relay 103 causes the release of line relay 102. Relay 309 when 20 operated renders line finder 204 busy and relay 102 in releasing removes ground from the conductor 151 whereby the driving magnets of finders 201 and 203 are deenergized. The calling line 101 is now extended through 25 springs of brush 239, back contacts of relay 314 to the trunk 352. Relay 102 in releasing also brings about the release of relays 308 and 310 but relay 311 remains locked under the control of relay 312.

30 It will be noted that duplicate sets of test relays as 313 and 315 are provided. The test relays 313 and 315 are effective when the calling lines are situated in either No. 0 or No. 1 panels whereas, test relays 308 and 35 310 are effective when the calling lines are located in panels No. 2 and No. 3. Should therefore calls be initiated simultaneously on corresponding lines terminating in No. 1 and No. 3 panels or corresponding lines terminating in panels No. 0 and No. 2 the line 40 terminating in the lower numbered panel will be given the preference. For example, assume that a call is initiated on line 104 simultaneously with the initiation of a call 45 on line 101, and assume that these lines occupy corresponding positions in their respective panels. Since brushes 237 and 239 are tripped in synchronism then at the time brush 239 locates calling line 101, brush 237 50 will also be positioned on the terminals of calling line 104. In this case test relays 313 and 315 will be operated over circuits similar to those described in connection with relays 310 and 308. Relays 313 and 315 will 55 be operated over a circuit traceable from ground through the winding of relay 313, both windings of relay 315, conductor 354, hunting spring of brush 237, to battery over the hunting conductor 153 which has battery applied to it in a manner similar to that 60 described in connection with line 101. Relay 313 in operating prevents the operation of relay 311 at this time and causes the operation of switching relay 314 by means of an 65 obvious circuit. Relay 314 in operating ex-

tends the tip and ring conductors of the calling line 104 to the trunk 352. Relay 313 also opens the circuit of the downdrive magnet 249 causing the brush rod 258 to come to rest. Brush 239 is now in contact 70 with the calling line 101 but line 101 is not connected to the trunk 352 because of the operation of the switching relay 314. Therefore the cut off relay 102 is not operated at this time and the start wire 151 remains grounded thus causing the other hunting line finders 201 and 203 to continue hunting until the line 101 is located. When the switching relay 314 operates as described 75 a circuit is completed from battery through the right winding of relay 311, right contact of relay 304, locking contact of relay 314, conductor 356, to ground through the front contacts of relay 313. Relay 311 completes a locking circuit traceable through 80 its left winding, left inner contacts, thence through the contacts of relay 312 to ground at the outer front contact of relay 311. This ground is also extended through the winding of relay 309, left outer armature and 85 front contact of relay 314, conductor 357, sleeve contact of the multiple brush 237, and thence to the sleeve conductor of line 104, to battery through the winding of cut off relay 90 103 which operates in series with relay 309 95 in the manner already described. The operation of the cut off relay 103 causes the release of relay 106 which removes the hunting condition from conductor 153 thus causing the release of relays 315 and 313. Since 100 cut off relay 103, however, is not energized because of the operation of switching relay 314, relay 102 remains operated and the starting condition continues to exist on conductor 151. Consequently the other line 105 finders 201 and 203 continue to hunt under control of relays 306, 318, 316, 317, etc., until the calling line 101 is located.

In Fig. 2 of the drawing it will be noted 110 that the circuits of the updrive magnets are shown prepared by means of the transfer switches 236, etc. In practice, however, certain line finders may have the updrive circuits prepared while others will have the downdrive circuits prepared depending upon 115 the position last assumed by the various line finders in their hunting operation. For example, as a result of the previous operation of transfer switch 259, the upper contact instead of the lower one may be closed. In 120 this case when line relay 102 operates as already described, the downdrive magnet 261 is energized and brush 238 which has been previously tripped, descends and seizes the calling line 101.

125 From this it will be seen that where a large number of line finders are employed at any instant, certain of the line finders will be nearer than others to a particular line when a call is initiated on this line and 130

this taken in conjunction with the fact that the brush on the front of the bank may be hunting upwardly while the corresponding brush on the rear of the bank may be hunting downwardly for the same line greatly reduces the hunting time of the line finders. In addition when subscribers of two lines correspondingly situated in different panels initiate calls simultaneously a plurality of finders may start to hunt simultaneously for these lines.

What is claimed is:

1. In an automatic telephone system, telephone lines, an automatic switch adapted for movement in different directions comprising fixed terminals in which said lines terminate and a plurality of brushes arranged to be moved as a unit, certain of said brushes adapted to hunt for electrically distinguished lines only during one movement of said switch and other of said brushes adapted to hunt for electrically distinguished lines only during a different movement of said switch.

2. In an automatic telephone system, telephone lines, a two-movement automatic switch comprising fixed terminals and a plurality of brushes arranged to be moved as a unit, means for causing certain of said brushes to hunt for electrically distinguished terminals only during one movement of said switch, and means for causing other of said brushes to hunt for electrically distinguished terminals only during a different movement of said switch.

3. In a telephone system, calling lines, an automatic switch adapted for reciprocating motion and comprising a plurality of sets of brushes arranged to be moved as a unit, means for causing one set of brushes to hunt for calling lines during only one-half of the motion of said switch, and means for causing another of said sets of brushes to hunt for calling lines during only the other half of the motion of said switch.

4. In an automatic telephone system, calling lines, a plurality of panel type line finders, each finder comprising a plurality of sets of multiple brushes arranged to be moved as a unit, a switch for each line finder for controlling the direction of movement thereof, each switch controlled by the movement of the associated finder, means for causing one set of brushes of a finder to hunt for calling lines during one position of the associated switch, and means for causing another set of brushes on said finder to hunt for calling lines during another position of said switch.

5. In combination, telephone lines, an automatic switch comprising a row of circuit terminals in which said lines terminate, a plurality of multiple brushes arranged to be moved in opposite directions over said ter-

minals, means for causing certain of said brushes to seize circuit terminals during only one direction of movement, and means for causing other of said sets of brushes to seize terminals during only a different direction of movement.

6. In combination, telephone lines, an automatic switch comprising a row of circuit terminals in which said lines terminate, a plurality of pairs of brushes normally out of contact with said terminals, means for bringing one brush of a pair into cooperative relation with said terminals, and means for simultaneously taking the other brush of a said pair out of cooperative relation with said terminals.

7. In combination, telephone lines, an automatic switch comprising a row of circuit terminals in which said lines terminate, a plurality of pairs of multiple brushes normally out of contact with said terminals, means for bringing one pair of multiple brushes into contact with said terminals, and means for simultaneously taking another pair of multiple brushes out of contact with said terminals.

8. In combination, telephone lines, an automatic switch comprising a row of circuit terminals in which said lines terminate, a plurality of groups of multiple brushes each group adapted to be moved as a unit, each brush having a tripped and set positions, means for tripping the brushes in certain groups, and means for simultaneously setting the brushes in the other groups.

9. In combination, telephone lines, an automatic switch comprising a row of circuit terminals in which said lines terminate, a plurality of groups of multiple brushes each group adapted to be moved as a unit, each brush having a tripped and a set position, and means for simultaneously tripping the brushes of certain groups and for setting the brushes of the other groups after the last terminal in said row has been reached.

10. In combination, telephone lines, an automatic switch adapted for movement in different directions comprising a row of circuit terminals in which said line is terminative, a plurality of groups of multiple brushes adapted to be moved as a unit, each brush having a tripped and a set position, and means for simultaneously tripping one group of brushes and for setting another group of brushes when the limit of motion of said switch in any direction has been reached.

11. In an automatic telephone system, a plurality of telephone lines, a plurality of line finders having no normal position, means responsive to the initiation of a call on one of said lines for starting all of said line finders which are idle, means for causing said line finders to hunt for said line only during one direction of movement, and

means for causing other of said line finders to hunt for said line only during a different direction of movement.

12. In an automatic telephone system, a plurality of lines arranged in groups, a plurality of line finders arranged in groups, each line finder carrying a plurality of brushes, each brush corresponding to one of said groups of lines, means responsive to the initiation of a call on one of said lines for starting a plurality of line finders, means for causing brushes corresponding to the particular group in which the calling line is located to hunt for said line only during downward movement, and means for causing other brushes corresponding to said particular group to hunt for said line only during upward movement.

13. In combination, telephone lines, an automatic switch comprising fixed terminals in which said lines terminate, a plurality of sets of multiple brushes arranged to be moved continuously upwardly and downwardly

over said terminals, means for tripping certain sets of said brushes when the limit of upward movement is reached, and means for tripping other of said brushes when the limit of downward movement is reached.

14. In combination, telephone lines, an automatic switch comprising fixed terminals in which said lines terminate, a plurality of sets of brushes arranged to be moved continuously in an upward and downward direction over said terminals, means for tripping a first set of said brushes and for simultaneously resetting a second set of said brushes when the limit of upward movement is reached, and means for tripping a third set of brushes and simultaneously resetting a fourth set of brushes when the limit of downward movement is reached.

In witness whereof, I hereunto subscribe my name this 24th day of March, A. D. 1925.

WILLIAM H. MATTHIES.
